UNITED STATES PATENT OFFICE.

FLOYD J. BELL, OF MEADVILLE, PENNSYLVANIA, ASSIGNOR OF ONE-HALF TO E. J. PRENATT, OF MEADVILLE, PENNSYLVANIA.

CORK-REMOVER.

1,117,764.

Specification of Letters Patent. Patented Nov. 17, 1914.

Application filed March 16, 1914. Serial No. 825,092.

To all whom it may concern:

Be it known that I, FLOYD J. BELL, a citizen of the United States of America, residing at Meadville, in the county of Crawford and State of Pennsylvania, have invented certain new and useful Improvements in Cork-Removers, of which the following is a specification, reference being had therein to the accompanying drawing.

10 This invention relates to bottle seals, and more particularly to devices that are adapted to remove the same from a bottle.

The object of this invention is to provide a simple device that will remove the seal 15 from a bottle without aid of any foreign or specially constructed implement.

Another object of this invention is to provide a seal remover for a bottle that is positioned between the cap and the disk on the 20 inside of the cap which completes the sealing of the bottle and extends from under said cap and lies snugly upon the outside of the same, thereby providing a device which is not likely to be engaged by any 25 foreign object or be any more cumbersome than a bottle which is not provided with the same.

A still further object of this invention is the production of a seal remover which is 30 positioned as above described which engages the cap and the sealing disk on the inside of the cap across the central portions thereof so as to obviate any chance of the device from slipping or being accidentally removed from between the cap and sealing disk.

A still further object of this invention is the production of a device of the kind above described which is simple in construction, 40 efficient in operation, and consists of the minimum number of parts.

In the accompanying drawing:—Figure 1 is a vertical section of the top end of the neck of the usual bottle with the seal mounted thereon and the improved seal remover in engagement therewith. Fig. 2 is an inverted view of the seal remover shown applied to a cap. Fig. 3 is a side elevation of the improved remover in the position which 50 it will assume when it is desired to remove the seal from a bottle. Fig. 4 is a perspective view of the device as shown applied to the seal of a bottle in Fig. 1.

Referring to the parts by reference numerals 10 designates the neck of a bottle 55 which is provided with the usual beads 11 and 12 formed adjacent the top edge thereof, thus providing the usual circumferential groove 13. The usual seal for a bottle is shown and the holder or cap is designated 60 by the numeral 14 and the sealing member which is positioned on the inside of the cap and engages the top edge of the bottle as designated by 15. This sealing disk is 65 usually formed of cork.

The improved seal remover is formed of a single strand of wire and has laterally extending parallel fingers 16 positioned between the holder or metallic cap 14 and the sealing disk 15 and engages said disk and 70 cap across the central portions thereof to prevent any accidental removal of the members at the edge of the disk 15. These parallel fingers 16 terminate at one end in the loop or jaw member 17 which comprise an 75 inner member 18 which is positioned on the inside of the metallic holder or cap to the outer member 19 which is positioned on the outside of the metallic holder or cap, these 80 said members 19 follow the upper surface thereof. The strand extends to form the lifting loop 20 which normally conforms in contour to the shape of the cap 14 so as to rest snugly thereon. As shown in Fig. 1 this finger engaging loop is bent downwardly on the opposite side of the holder or cap from that of the jaw 17 and thus 85 there are no projecting members which are liable to engage a foreign object and loosen the holder from the cap and in many cases 90 remove the seal from the bottle.

What is claimed as new, is:—

1. A pulling device for bottle-caps formed from a single strand of wire and comprising a U-shaped jaw, an integral lifting loop extending from said jaw, said U-shaped jaw adapted to clamp on the annular flange of a cap whereby a cap may be lifted from engagement with a bottle by drawing upon said loop, said jaw being adapted to 95 impart a direct pull upon a cap thereby preventing the device from being pulled from engagement with a cap.

2. A pulling device for bottle-caps formed from a single strand of wire comprising 100 parallel fingers, said fingers adapted to fit 105

within a bottle cap, integral U-shaped jaws formed upon said fingers, said jaws terminating in an integral lifting loop, said jaws adapted to fit over and clamp upon the annular rim of a bottle cap, said loop being adapted to be drawn upwardly to cause said jaws to impart a direct pull to a cap by said jaws, whereby said jaws will lift a

cap from engagement with a bottle without being bent out of shape.

In testimony whereof I hereunto affix my signature in presence of two witnesses.

FLOYD J. BELL.

Witnesses:

E. J. PRENATT,

MAUDE HARPER.
